CLAIM

I claim the ornamental design for a pet feeder, as shown and described.

DESCRIPTION

FIG. 1 is a perspective view of a pet feeder according to an embodiment.

FIG. 2 is a perspective view of the pet feeder of FIG. 1, viewed from another aspect.

FIG. 3 is a front view of the pet feeder of FIG. 1.

FIG. 4 is a rear view of the pet feeder of FIG. 1.

FIG. 5 is a left side view of the pet feeder of FIG. 1.

FIG. 6 is a right side view of the pet feeder of FIG. 1.

FIG. 7 is a top view of the pet feeder of FIG. 1.

FIG. 8 is a bottom view of the pet feeder of FIG. 1; and,

FIG. 9 is a perspective view of the pet feeder of FIG. 1, showing the pet feeder in a state of use. The broken line showing of the environment is for illustrative purposes only and forms no part of the claimed design.

1 Claim, 9 Drawing Sheets
